Primary Examiner — Mehri F Bajoul(74) *Attorney, Agent, or Firm* — Daniel F. Nesbitt; Nesbitt IP LLC(57) **CLAIM**

I claim the ornamental design for a spinning top case, as shown and described.

DESCRIPTION

FIG. 1 is a top, front, left perspective view of my new design for a spinning top case.

FIG. 2 is a front view thereof.

FIG. 3 is a rear view thereof.

FIG. 4 is a left side view thereof, the right side view being a mirror image.

FIG. 5 is a top view thereof.

FIG. 6 is a bottom view thereof.

FIG. 7 is a bottom, front, left perspective view thereof.

FIG. 8 is a left side sectional view thereof, taken through line 8-8 of FIG. 1; and,

FIG. 9 is a front sectional view thereof, taken through line 9-9 of FIG. 1.

The dashed broken lines shown in FIGS. 8 and 9 show environment only.

1 Claim, 9 Drawing Sheets(56)
